Att 342

UNITED STATES PATENT OFFICE.

EDMUND C. MORGAN, OF NEW YORK, N. Y.

MINING AND LOADING MACHINE.

Application filed November 15, 1915, Serial No. 61,481. Renewed September 16, 1919. Serial No. 324,230.

To all whom it may concern:

Be it known that I, EDMUND C. MORGAN, a citizen of the United States, residing at New York, in the county of New York and State of New York, have invented certain new and useful Improvements in Mining and Loading Machines, of which the following is a specification.

This invention relates to mining machines for severing coal or other material from its native bed, and for transferring the severed material to a position to be loaded into a car or other transporting means. The invention consists in the combination and arrangement of parts set forth in the following specification, shown in the accompanying drawings, and more particularly pointed out in the appended claims.

In the drawings—

Fig. 1 is a side elevation of a complete mining machine in position in a mine chamber.

Fig. 2 is a top plan view of the machine shown in Fig. 1.

Fig. 3 is a longitudinal sectional view of the machine shown in Fig. 1 substantially on the center line thereof.

Fig. 4 is a horizontal sectional view substantially on line 4—4 of Fig. 3.

Fig. 5 is a horizontal sectional view looking upward on line 5—5 of Fig. 3.

Fig. 6 is a central longitudinal sectional view of the operating mechanism for the cutter and associated parts on a plane at right angles to the cutter frame.

Fig. 7 is a transverse sectional view substantially on line 7—7 of Fig. 6.

Fig. 8 is a transverse sectional view substantially on line 8—8 of Fig. 6.

Fig. 9 is a central longitudinal sectional view of the cutter operating mechanism taken on a plane parallel with the cutter frame.

Fig. 10 is a transverse sectional view on line 10—10 of Fig. 6.

Fig. 11 is a fragmentary sectional view on line 11—11 of Fig. 6.

Fig. 12 is a transverse sectional view on line 12—12 of Fig. 9, the outer cylinder not being shown.

Fig. 13 is a side elevation of the cutter head and associated parts of a modified form of the invention.

Fig. 14 is a top plan view of the mecha-

nism shown in Fig. 14, part of the mechanism being sectioned on line 14—14.

Fig. 15 is a fragmentary side elevation of the cutter bar and chain used in this invention.

Fig. 16 is a front view of the mechanism shown in Fig. 15.

Fig. 17 is a section on line 17—17 of Fig. 15.

Fig. 18 is a plan view of the cutter frame.

Fig. 19 is a fragmentary detail showing the corner construction of the cutter frame.

Referring to the drawings, the numeral 1 designates a frame on which the various operating parts which comprise the present invention are mounted. Frame 1 includes a pair of side plates 2, having their lower portions connected by a base plate 3, and having their upper portions connected by a pair of cross bars 4 and 5, one at each end of the frame.

Supported by the stationary frame 1, and arranged to swing thereon to various operating positions, is a movable frame 6, having side bars 7 connected at their bottom edges by a base plate 8, and having a conveyor bed plate 9 extending from one bar 7 to the other, and positioned above the base plate 8. The frame 6 is pivotally supported at its rear end on the cross bar 5 of the main frame 1, as best shown in Fig. 3, by means of a bearing 10 and a pivot bolt 11. Secured to the lower side of the forward portion of the movable frame 6 is a transversely extending arcuate bar 12 arranged to rest upon the bar 4. The bar 4, as best shown in Fig. 5, is also arcuate in shape, the center of curvature of the two bars being located at the center of the pivotal connection between the frames 1 and 6. It is thus seen that the bars 4 and 12 form a track or slideway for supporting the frame 6 as it is swung about the pivot bolt 11. The inner edge of the bar 4, as shown in Fig. 5, is provided with rack teeth 13, and mechanism is carried by the frame 6 provided with a pinion arranged to mesh with these teeth to move the frame 6 relative to the frame 1 in a manner to be described.

Carried by the lower surface of the base plate 8 of the movable frame 6, Figs. 1, 3 and 5, is a motor 14 which drives a pinion 15 (Fig. 5) arranged to mesh with a gear 16 mounted for rotation on a counter-shaft 17. Concentric with the gear 16, and integral

75

90

95

100

105

therewith, is a pinion 18 arranged to mesh with a gear 19 rigidly secured to a shaft 20 (Fig. 3) carried by a bracket 21 also secured to the lower surface of the base plate 8. Mounted for rotation on the shaft 20 is a worm 22 (Fig. 5) arranged to mesh with a worm gear 23 rigidly secured to the lower end of the vertical shaft 24, which is also supported by the bracket 21. Rigidly secured to the vertical shaft 24, and operating in an opening in the bracket 21 above the worm wheel 23, is a pinion 25 arranged to mesh with the teeth 13 on the arcuate cross bar 4 carried by the main frame 1. A clutch 26 is slidably mounted on the shaft 20, and is arranged to clutch the worm 22 to the shaft 20 for rotation therewith. A rod 27 extending transversely of the machine frame is arranged to operate the clutch 26, and is provided at each side of the machine with operating handles 28. It will be seen that by this train of gearing the operator, by moving one of the handles 28, may connect the motor 14 with the pinion 25, and cause said pinion to rotate in mesh with the teeth 13 on the stationary arcuate rack bar 4. Since the pinion 25 has its axis fixed relative to the movable frame 6, rotation of this pinion will cause the frame 6 to swing about the pivot 11, and move the forward end of the frame on the arcuate plate transversely of the main frame 1. Splined to the shaft 17 is a clutch 30, operated by a bar 31 extending transversely of the machine, and provided with handles 32 mounted on each side of the machine frame. The clutch 30 is arranged to secure the shaft 17 to the gear 16 for rotation therewith, and thus drive the beveled pinion 33 carried at the end of this shaft, as shown more particularly in Figs. 1 and 5. The beveled pinion 33 is arranged to drive a chain of gearing comprising the pinions 34, 35, 36, 37 and 38, (Fig. 1) and including the shafts 39 and 40. The pinion 38 is rigidly secured to the end of a shaft 41 extending transversely of the movable frame 6 at the rear end thereof. The shaft 41, as shown in Fig. 3, carries a series of sprocket wheels 42 arranged to drive a conveyor belt 43 which extends longitudinally of the frame 6, and which has its upper run supported by the bed plate 9 and its lower run supported by the base plate 8 of this frame. The forward end of the conveyor 43 travels over a roller 44, mounted for free rotation on a shaft 45 which extends transversely of the frame 6 near the forward end thereof. It will be apparent from the drawing and description that the operator, by moving one of the handles 32, may connect the motor 14 through the train of gearing described, with the conveyor belt 43, to cause this belt to travel over its bed plate 9.

Mounted on the base plate 3 of the main frame 1 is a motor 46, Figs. 3 and 4, ar-

ranged to drive a shaft 47 through a train of gearing 48. Mounted for free rotation on the shaft 47 is a pair of drums 49 and 50, and a pair of clutches 51 and 52 are arranged to clutch the drums 49 and 50 respectively with the shaft 47 to rotate therewith. The clutches 51 and 52 are independently controlled by bars 53 and 54 respectively, extending transversely of the machine frame, and each provided with two pairs of levers 55 and 56, one lever positioned at each side of the machine for operating each of the bars 53 and 54 respectively. Secured to the drums 49 and 50 respectively, and arranged to wind thereon, are two cables 57 and 58. These cables pass through pairs of leaders 59 located one at each side of the main frame 1 for guiding the cables to the sides of the mine chamber. The cables 57 and 58 are provided with hooks 60 arranged to be engaged with mine props 61, which may be secured at suitable positions in the mine chamber. By properly positioning the props 61, and by winding cables 57 and 58 on the drums 49 and 50, the mining machine may be moved forwardly in the mine chamber as occasion requires, or shifted from one side thereof to the other if at any time such shifting becomes desirable.

As shown in Figs. 1, 2 and 3, the side bars 7 of the movable frame 6 extend forwardly, and are provided at their front ends with bearing rings 62. Mounted for rotation in bearing rings 62, as best shown in Figs. 6 and 9, is a hollow frame or axle 63, which is split into two sections along a central plane, as indicated in Figs. 6, 7 and 8, and which carries interiorly thereof the operating mechanism for the cutter and co-operating parts. The hollow axle 63 is provided with a series of transverse webs 64, 65 and 66, which are provided with bearings 67, 68 and 69 respectively, in which are independently journaled a pair of motor armatures 70 and 71. A shaft 72 of the armature 71 is extended to the left, Figs. 6 and 9, and is supported at its end by an additional transverse web 73. This shaft 72 has rigidly secured thereto a worm 76' and a pinion 75. The worm 76' is arranged to mesh with a worm gear 76 carried on a transverse shaft 77, which is provided with a second worm 78, Figs. 6 and 7, which meshes with a worm wheel 79 carried by a shaft 80 extending longitudinally of the axle 63 near the periphery thereof, and mounted in a bearing 81 rigid with the axle 63. On the end of the shaft 80, opposite the worm wheel 79, is a pinion 82 arranged to mesh with the teeth of an internal gear 83, as shown in Figs. 6 and 10. The internal gear 83, as shown in Fig. 6, is provided with an offset portion 84 which fits into the bearing 81, and is rigidly keyed thereto by keys 85. The interior of the offset portion 84

70

110

115

120

125

130

is shaped to form a circular bearing surface 86, in which the end portion 87 of the hollow axle 63 is journaled. Since the internal gear 83 is held rigidly by the bearing 62 in 5 the forwardly extending portion of the arm 7 it will be seen that rotation of the pinion 82 will cause this pinion to travel around the interior of the gear 83, and since the bearing 81, which supports the pinion 82, is 10 rigid with the axle 63, the movement of the pinion 82 will cause the entire axle to rotate in the bearing 62. It should be noted that two worm gears are interposed between the armature 71 and the pinion 82, and that the 15 rotary movement of the hollow axle 63 will therefore be a slow and very powerful movement. The worm gears also serve to hold the hollow axle in whatever position it is turned to by the movement of the motor 20 comprising the armature 71.

The pinion 75 carried by the shaft 72 meshes with a gear 88 mounted for free rotation on a shaft 89 journaled in bearings secured to the webs 66 and 73. A clutch 90, 25 Figs. 6 and 7, is provided on the shaft 89 for clutching the shaft to the gear 88 to cause it to rotate therewith. The clutch 90 is operated by a rod 91 which extends longitudinally of the axle 63, and is provided 30 with an operating handle 92 positioned exteriorly of the axle at one end thereof, Fig. 1. The shaft 89 carries a pinion 93 arranged to mesh with a beveled gear 94 secured to the shaft 95, which is provided with a 35 sprocket wheel 96 located at one end of the axle 63. In this way the sprocket 91 may be driven by the armature 71, the movement of the sprocket being controlled by the clutch 90 and its operating lever 92.

40 The motor comprising the armature 70 drives a shaft 97, which has the end thereof adjacent to the end of the co-axial shaft 98. A friction clutch 99 is provided for clutching these two shafts together. The clutch 45 99 is operated by a rod 100 and a handle 101 mounted on the end of the axle 63. The shaft 98 carries a pinion 102, Figs. 6 and 12, which meshes with a gear 103 rigidly mounted on a shaft 104, which also carries a pinion 105. Pinion 105 meshes with a gear 106 50 mounted for free rotation on a stub shaft 107, which is rigidly carried in a bearing member formed integral with the axle 63. As shown in Figs. 6, 11 and 12, the teeth of 55 the gear 106 are arranged to project beyond the periphery of the axle 63 through an opening therein, for a purpose to be described.

Completely surrounding the axle 63 and 60 arranged for free rotation thereon, as shown in Figs. 2, 3, 6 and 9, is a sleeve or hollow cylinder 108. As indicated in Figs. 6 and 9, the sleeve 108 is journaled upon the axle 63 at each end, but is slightly spaced away 65 from the axle throughout the greater part of its length. The end of the sleeve opposite the gear 106 is provided with inwardly projecting gear teeth 109, Figs. 9 and 11. The teeth 109 are arranged to mesh with the teeth of the gear 106, and in this way the 70 sleeve 108 may be rotated relative to the axle 63 by moving the clutch 99, to connect the motor 70 through the train of gearing described above with the gear 106.

Attached to the ends of the hollow axle 63 75 are two plates 110 and 111 respectively. These plates are of sufficient diameter to extend over the sides of the bearing 62 to hold the parts in place relative to one another when the screws 112 are in proper position 80 to hold the plates 110 and 111 in place. Fastened to each of the plates 110 and 111 are two clamping members 113 and 114, held in place by cap screws 115. For the purpose of severing the material to be mined from 85 the mine wall, a U-shaped cutter bar 116 is provided, the legs of which are arranged to be clamped to the plates 110 and 111 by the clamping members 113 and 114. It will be apparent that the cutter bar 116 may be adjusted relative to the cutter head by loosening the cap screws 115, and sliding the legs of the bar between the plates 113 and 114. When the bar is properly positioned, the 90 cap screws 115 are tightened to hold it 95 rigidly in place. An endless cutter chain 117 is carried at the forward edge of the bar 116, and is caused to travel along this bar by the sprocket wheel 96 over which the chain passes, as shown in Fig. 9. It will be understood that the rotation of the hollow axle 63 by means of the armature 71, pinion 82 and connecting gearing, will move the cutter bar 116 to force said bar into the material 100 to be mined. Simultaneously with the feeding of the bar into the material, the chain 117 will be driven by the same motor through separate gearing, to form a kerf 105 for the cutter.

As best shown in Figs. 1, 2 and 3, the 110 cylinder or sleeve 108 has secured to one side thereof, and extending transversely of the machine for its entire width, a hopper-shaped member. This member consists of two arms 119, one at each end of the hopper, 115 and two plates 120 and 121 extending longitudinally of the hopper from one arm 119 to the other. The plate 120 extends tangentially at one of its edges from the sleeve 108, and the other edge of this plate meets with 120 one of the edges of the plate 121 at 122, to form with the arms 119 a closed pocket or hopper. As will be seen from Fig. 3, a portion of the wall of the sleeve 108 is removed 125 adjacent the hopper 118. This is to permit access to the axle 63 enclosed within the sleeve. It will be seen from Figs. 6 and 9 that the ends of the sleeve 108 co-operate with the transverse walls of the axle 63 and with inwardly projecting ribs 123 carried 130

by the sleeve 108 to form closed grease pockets in which the gearing for driving the various parts operates.

Extending between the side walls 7, and pivotally mounted thereon at 124, is a chute or slideway 125, having side walls 126, and bridging the space between the end of the conveyor chain 43 and the upper portion of the sleeve 108. The chute 125 has its forward edge 127 beveled to fit closely against the periphery of the sleeve 108, as shown in Fig. 3.

The operation of the parts thus far described may now be understood. The machine is placed in a mine chamber, as shown in Figs. 1, 2 and 3, and hopper 118 and the cutter bar 116 being swung in a clockwise direction, as viewed in the drawings, until the portion 122 of the hopper 118 contacts with the chute 125, lifting the chute about its pivot 124, and permitting the hopper to occupy a position between the sides 7 of the movable frame 6. The cutter bar 116 will then occupy a position just back of that occupied by the portion 122 of the hopper 118, as shown in Fig. 1. With the parts thus positioned, the armature 71 will be energized to drive the chain 117 and to rotate the axle 63 to feed the cutter bar 116 into the material to be mined, thus forming a kerf 128, and severing a section of material 129 from the wall of the mine, as shown in Fig. 1. As the axle 63 rotates, it will carry the stub shaft 107 and the gear 106 around with it. If the sleeve 108 and the hopper 118 remain stationary, this will cause a rotation of the train of gearing connected with the gear 106. The rotation of this gearing will cause a certain amount of drag, due to the friction of the gearing upon the sleeve 108, tending to rotate the sleeve in unison with the cutter bar 116. This usually will be sufficient to bring the hopper 118 into the position shown in Fig. 1, where it is stopped by contact with the section of severed coal. If the drag caused by the gearing alone is not sufficient, the clutch 99 may be locked, and the resistance of the armature 70 to rotate be added to that of the train of gearing. As the cutter bar 116 continues its operation, the drag on the gear 106 will continue to hold the hopper 118 in position. After the cutter 116 has reached its uppermost position and completely severed the section of material 129 from the mine wall, the motor 71 is stopped, and the cutter is held in position by the worm gearing by which it is driven. The motor 70 is now actuated, and the clutch 99 thrown in to rotate the gear 106. Since the shaft 107 on which the gear 106 is mounted is held from rotation by the worm gear by which the hollow axle 63 is driven, rotation of the gear 106 will cause the sleeve 108 to revolve about the axle 63, and carry the hopper 118 upwardly in a counter-clockwise

direction, as viewed in Figs. 1 and 3. This movement of the hopper will force the severed material upwardly before it and through the loop formed by the cutter bar 116 onto the chute 125. If the material breaks apart it will be held from escape by the presence of the sleeve 108 and by the hopper 118. When the material is deposited upon the chute 125 it will slide downwardly and backwardly onto the conveyor 43, which is driven by the motor 14 in the manner previously described, to transfer the material to the rear end of the machine, where it is discharged into a car 130 carried on a track 131.

As shown in Fig. 2, the mine chamber is of sufficient width to permit of three cuts being made side by side across the width of the chamber. To position the machine for making these cuts, the movable frame 6 is swung laterally about the pivot 11 to bring the cutter bar 116 in the proper position for making the various cuts. This swinging movement is accomplished by means of the motor 14 and the pinion 25 in the manner previously described. After each series of cuts has been made, the machine is moved forwardly into position to make a second series by means of the cables 57 and 58 and their co-operating mechanism. Since the movable frame 6 swings about a pivot located substantially at the rear end of the frame, the lateral movement of the frame will not disturb the proper position of the discharge end of the conveyor 43 relative to the car 130.

The construction of the cutter bar and chain will best be understood by reference to Figs. 16 to 19 inclusive. The cutter bar 116, as shown in Fig. 18, is U-shaped, and has secured to its forward edge a slideway 105 made up of straight sections 132 and corner sections 133. The slideway is secured to the cutter bar 116 by rivets 134, and is provided with a groove 135 for guiding the cutter chain 117. The slideway is made in sections 110 as shown to facilitate the process of construction. The groove 135 may be formed in straight sections on a milling machine, and the corner sections 133 may be formed from a complete ring which has the groove 135 machined therein on a lathe. The chain 117 is provided with links 136, having forwardly projecting bit sockets 137 carrying bits 138 for cutting the material to be mined. Guide lugs 139 extend rearwardly from the links 136, and fit into the groove 135. The lugs 139 and the groove 135 are given two right angle turns, as shown in Fig. 17, to prevent lateral play of the chain relative to the cutter bar. Spring pressed friction devices 140 are provided for holding the bits 138 in place, and spring clips 141 are arranged for detachably holding the links of the chain together.

In Figs. 13 and 14 is shown a modified

form of cutter head used in mines where the coal breaks up readily. In this form of cutter head the severed coal is completely enclosed, so that there is no opportunity for 5 finely broken particles to escape. As shown in Fig. 13, the hopper 118 is made deeper than in the form shown in Fig. 1, and the legs of the cutter bar 116 are provided on their lower edges with sheet metal guards 10 142 which are arcuate in form, and which overlap the sides of the hopper 118. By this construction the sides of the cut are completely closed, and all of the fine particles 15 of coal are prevented from escaping. In Fig. 14 of the drawings, the lines of the cut made in the material to be mined are represented by broken lines. In Fig. 13 is shown a pivoted stop member 143. This member may be thrown into inoperative position as 20 shown in broken lines in the Fig. 13, or may be swung into the position shown in full lines, for holding the hopper 118 in position to meet the section of severed material, to prevent the hopper from swinging downwardly and backwardly during the cutting 25 operation under the weight of detached portions of the material in case the drag caused by the train of gearing connected with the gear 106 is insufficient to hold the hopper in place while the cutter is being operated.

What I claim as new, and desire to secure by Letters Patent of the United States is:—

1. In a mining machine, the combination with core-cutting mechanism having an unobstructed core opening therethrough, of means for operating said core-cutting mechanism including upward swinging feeding movement thereof about a substantial horizontal pivotal axis, means separate and independent from said core-cutting mechanism for moving the core from the position it occupied in its native bed upwardly and backwardly through the opening in said core-cutting mechanism, and a conveyer in position for receiving the material thus moved from the mine wall.

2. In a mining machine, the combination with core-cutting mechanism having an unobstructed core opening therethrough, of a hopper for receiving the cut material, means for operating said core-cutting mechanism including upward swinging feeding movement thereof independently of movement of said hopper, and means for swinging said hopper upwardly to discharge the cut material to a position from which it may be transported.

3. In a mining machine, the combination with core-cutting mechanism, of a hopper having its wall shaped to conform to the core cut by said core-cutting mechanism, means for supporting said hopper for movement into position to bring its walls adjacent the lower portion of said core so that 60 the hopper may receive the material of the

core, and means for moving said hopper to discharge the dislodged material therefrom.

4. In a mining machine, the combination with a core cutter having an unobstructed core opening therethrough and comprising 70 chain cutting mechanism, of means for operating said core cutter to cut a core in a single feeding movement, a hopper for receiving the material severed by said core cutter, and means for moving said hopper 75 and said core cutter independently of each other but about a common axis of arcuate movement.

5. In a mining machine, the combination with cutting mechanism for severing material to be mined by forming a kerf in said material, of a hopper having walls arranged to conform to the kerf made by said cutting mechanism, means for supporting said cutting mechanism and said hopper for 80 arcuate movement on the same axis, and means for swinging said hopper upwardly about such axis for carrying the material severed by said cutting mechanism into a 85 position from which it may be transported. 90

6. In a mining and loading machine, the combination with core-cutting mechanism having an unobstructed core opening therethrough, of transferring mechanism having a receiving portion located above the axis of movement of said core-cutting mechanism, means for moving the severed material upwardly from the position it occupied in its native bed into position for discharge onto said receiving portion of said transferring 100 mechanism, and means for operating said core-cutting mechanism including upward swinging feeding movement thereof on its said axis independently of upward movement of said discharging means.

7. In a mining and loading machine, the combination with a supporting frame, of core-cutting mechanism mounted to swing on a substantially horizontal axis on the forward end of said frame, a conveyer extending longitudinally of said frame, a hopper mounted on said frame in position to receive dislodged material of said core, means for operating said core-cutting mechanism including upward swinging feeding movement thereof while said hopper remains relatively stationary, and means for swinging said hopper upwardly about the horizontal axis of said core-cutting mechanism to discharge the dislodged material in 110 said hopper onto the forward end of said conveyer. 115

8. In a mining machine, the combination with a supporting frame, of cutting mechanism supported at one end of said frame, 125 a slideway carried by said frame and extending rearwardly and downwardly from said cutting mechanism when the latter is in its upper position, means for operating said cutting mechanism including feeding move- 130

- ment thereof to such upper position, and means mounted for movement independent of said cutting mechanism for receiving the severed material and discharging the same onto said slideway.
9. In a mining machine, the combination with a supporting frame, of a conveyer mounted on said frame to extend longitudinally thereof a cutter head carried by 70 said frame, a slideway pivotally connected to said frame and movable into position to bridge the space between a part of said cutter head and the forward end of said conveyer, and means separate and independent 75 from said slideway for discharging material from said cutter head over said slideway onto said conveyer.
10. In a mining machine, the combination with a supporting frame, of conveyer mechanism carried thereby, a cutter head carried by 80 said frame, a slide mounted on said frame to bridge the space between said cutter head and said conveyer mechanism, and means movable independently of said slide 85 for discharging material from said cutter head over said slide onto said conveyer mechanism.
11. In a mining machine, the combination with a supporting frame, of conveyer mechanism mounted thereon, a cutter head, a bridge in sliding engagement with said cutter head, means for supporting said cutter head on said frame for movement relatively to said bridge, and means for raising 90 material to discharge the same rearwardly over said bridge onto said conveyer mechanism.
12. In a mining and loading machine, the combination with a supporting frame, of 95 conveyer mechanism thereon, a drum mounted on the forward end of said supporting frame for partial rotation on a horizontal axis, core-cutting mechanism mounted on said drum and having an unobstructed core opening therethrough, and means mounted to have a swinging movement on substantially the same axis as said barrel frame to gather the dislodged material and discharge the same rearwardly over the top of said 100 drum onto said conveyer mechanism.
13. In a mining machine, a frame, conveyor mechanism carried by said frame, a rotary cutter head carried by said frame, a loop cutter carried by said cutter head and having an unobstructed core opening therethrough and movable about a horizontal axis to sever coal from its native bed, and means movable about the axis of said loop cutter to receive the severed material, raise 105 it into a position above a part of said cutter head and discharge it rearwardly from said cutter head onto said conveyor mechanism.
14. In a mining machine, a frame, a conveyor carried by said frame, a rotary cutter head carried by said frame, a chute mounted 110
- on said frame to bridge the space between the upper portion of said cutter head and said conveyor, a cutter for severing material from its native bed, and a hopper for receiving said material and arranged to swing upwardly about a horizontal pivot independently of movement of said cutter head to discharge said material rearwardly over the top of said cutter head onto said chute.
15. In a mining machine, a frame, a conveyor carried by said frame, a rotary cutter head mounted on the forward end of said frame, a chute pivotally carried by said frame and arranged to bridge the space between the forward end of said conveyor portion of said cutter head, a loop cutter carried by said cutter head for severing material from its native bed, a hopper shaped to conform to the severed material and movable into position to receive the lower portion of 115 said material during the cutting operation of said cutter, and means for swinging said hopper upwardly about the axis of said cutter independently of movement of said cutter head to raise the severed material above 120 said cutter head and to discharge said material through the opening formed by said cutter onto said chute.
16. In a mining machine, the combination with a supporting frame, of a cutter head 125 carried by said frame, a hopper rotatable into position for discharging material rearwardly therefrom, and a chute pivotally mounted on said frame in position to be in the path of movement of said hopper and to 130 be tilted thereby to a greater angle of elevation.
17. In a mining machine, a frame having two side members, a chute pivotally mounted between said side members, a cutter head 135 carried between said side members, and a hopper rotatably mounted on said cutter head, and movable into position to partially occupy the space normally occupied by said chute.
18. In a mining machine, a frame, a pair of side members carried by said frame, a cutter head pivotally mounted between said side members, a chute, a cutter carried by 140 said cutter head, a hopper mounted on said cutter head and arranged to rotate about the pivotal center of said cutter and to discharge material severed by said cutter rearwardly over said cutter head onto said chute, and means for swinging said hopper into a position normally partially occupied by said chute.
19. In a mining machine, the combination with a supporting frame, of cutting mechanism comprising a rotary axle carried by 145 said frame, a sleeve rotatably mounted on the exterior of said axle, and a device carried by said sleeve for removing the material severed by said cutting mechanism.
20. In a mining machine, the combination 150

with a supporting frame, of an axle mounted for rotation in said frame, a cutter carried by said axle, means for operating said cutter including arcuate feed movement thereof and arcuate movement of said axle, a cylindrical sleeve pivotally mounted on said axle and surrounding the same, said sleeve extending substantially the full length of said axle, and a hopper carried by said sleeve for movement independently of the movement of said axle in position to receive the material severed by said cutter.

21. In a mining machine, a frame having two side members, a hollow axle journaled in said side members, a cutter carried by said axle, mechanism mounted within said axle for operating said cutter, a sleeve surrounding said axle, means carried by said sleeve for moving the material severed by said cutter, and mechanism located within said axle for rotating said sleeve relative thereto.

22. In a mining machine, a frame, a hollow axle journaled for rotation in said frame, a cutter carried by said axle, mechanism located within said axle for rotating said axle and said cutter and adapted to hold said cutter to prevent rotary movement thereon, a device rotatably mounted on said axle for moving the material severed by said cutter, and means within said axle for rotating said last mentioned device relative thereto.

23. In a mining machine, a frame, a hollow axle rotatably mounted in said frame, a cutter carried by said axle, a hollow sleeve journaled on said axle, a material moving device carried by said sleeve, and independently operable motors mounted within said axle for rotating said axle and said sleeve independently of one another.

24. In a mining machine, a frame, a hollow axle rotatably mounted in said frame, a U-shaped cutter bar carried by said axle, an endless cutter mounted on said cutter bar, a sleeve journaled on said axle, a hopper carried by said sleeve having its walls movable into a kerf formed by said cutter, and means mounted within said axle for rotating said sleeve and hopper to cause said hopper to transfer material severed by said cutter to a position from which it may be transported.

25. In a mining machine, a frame, a hollow axle journaled in said frame, a cutter carried by said axle, mechanism mounted within said axle for rotating said axle and cutter, a motor for operating said rotating mechanism, said mechanism including a worm gear by which said axle is held from rotation other than by said motor, means rotatable about said axle for moving material severed by said cutter, and mechanism mounted within said axle for rotating said material-moving means relative to said axle.

26. In a mining machine, a frame, a hollow axle journaled in said frame, a sleeve concentric with said axle and journaled

thereon, a cutter carried by said axle, means carried by said sleeve for moving material severed by said cutter, and mechanism mounted within said axle for rotating said sleeve and axle about their common axis independently of one another.

27. In a mining machine, a frame, a hollow axle rotatably mounted in said frame, a cutter carried by said axle, a stationary gear concentric with said axle, a pinion carried by said axle eccentrically thereof and arranged to mesh with said gear, a motor operatively connected with said pinion through a chain of gearing arranged to drive in one direction only, a sleeve journaled on said axle, a device for moving material severed by said cutter carried by said sleeve, and a second motor mounted within said axle for rotating said sleeve relative thereto.

28. In a mining machine, an axle, a cutter carried by said axle, means for rotating said cutter and axle, a device rotatable relative to said axle for receiving material severed by said cutter, and a train of gearing connecting said axle and material-receiving device and arranged to be driven by relative movement of said axle and device, and to thus offer resistance to such relative movement whereby the rotation of said axle will tend to rotate said material-receiving device simultaneously therewith.

29. In a mining machine, a rotary cutter for severing material to be mined, a device movable relative to said cutter for receiving said material, and yielding mechanism tending to rotate said receiving device with said cutter whereby said receiving device is held stationary in operative position during the rotation of said cutter and ready to move when said cutter has completed its cut.

30. In a mining machine, a rotary cutter, a device for receiving material severed by said cutter, and a train of gearing arranged to be driven by relative movement of said receiving device and cutter whereby the inertia and resistance of said gearing will oppose such relative movement and cause said receiving device to be yieldingly held in operative position during the rotation of said cutter.

31. In a mining machine, a cutter, a device for receiving material severed by said cutter, a train of gearing arranged to be driven by relative movement of said cutter and material-receiving device whereby the inertia and resistance of said gearing will tend to prevent such relative movement and to hold said receiving device in operating position during the rotation of said cutter, and a motor for driving said gearing to cause said material-receiving device to move the material severed by said cutter into position from which it may be transported.

32. In a mining machine, a frame, a sleeve

125

130

- 8
32. In a mining machine, a frame, a sleeve journaled for rotation in said frame, a hopper carried by said sleeve, and means located within said sleeve for rotating the latter and the hopper to move material received thereby 5 upwardly into position to be discharged rearwardly over said sleeve.
33. In a mining machine, a frame, a sleeve journaled for rotation in said frame, a hopper carried by said sleeve comprising a rear 10 wall arranged tangentially to said sleeve at one edge thereof, a front wall concentric with said sleeve and meeting said rear wall at the edge thereof opposite that which is tangent to said sleeve, and arms normal to 15 said sleeve and arranged to form end walls for said hopper.
34. In a mining machine, the combination with a supporting frame, of an axle journaled on said frame, a hopper carried 20 by said axle and rotatable therewith, and means carried wholly by said axle for moving itself and said hopper in an arc relatively to said supporting frame to move a load in 25 said hopper to discharging position.
35. In a mining machine, a frame, a cutter, rotatably mounted on said frame, for forming an arcuate cut in the material to be mined, and a hopper rotatable in said frame about the axis of rotation of said 30 cutter independently of movement of said cutter bodily, and having an exterior wall curved to conform to the curvature of said arcuate cut, and having an interior wall extending from one edge of the exterior wall 35 to a point adjacent the axis of rotation of said cutter and hopper.
36. In a mining machine, a device for forming an arcuate cut in the material to be mined to sever a core of said material from 40 its native bed, mechanism for afterward raising said material upwardly from the position it occupied in its native bed to a position from which it may be transported, and means for enclosing said severed material during said operation.
37. In a mining machine, the combination with kerf-cutting mechanism, of means for operating the same including feeding movement thereof, a hopper mounted for movement independently of the feeding movement 50 of the kerf-cutting mechanism and having walls forming a pocket arranged to enter a kerf formed by said kerf-cutting mechanism to enclose the material during the continuance of the severing operation, and guards carried by said kerf cutting mechanism and arranged to cooperate with the walls of said hopper to enclose the material at its sides during the completion of the feeding movement of said cutting mechanism.
38. In a mining machine, a cutter head, a loop core cutter carried by said head and rotatable therewith to form an arcuate core 65 of mined material, a hopper having a closed bottom and walls shaped to conform to the material severed by said cutter, means for moving the walls of said hopper into the kerf formed by said cutter whereby a portion of the material severed by said cutter is enclosed in said hopper, and guards carried by said cutter arranged to co-operate with said hopper for enclosing the entire section of material severed by said cutter.
39. In a mining machine, a cutter, means for receiving the material severed by said cutter, mechanism operated upon feeding movement of said cutter for yieldingly holding said material-receiving means in operative position during such feeding movement of said cutter, and a supplemental device for positively holding said material-receiving means in said position.
40. In a mining machine, a core cutter, a hopper for receiving the material directly from the position thereof as left by said cutter, and a stop movable into operative relation with said hopper to hold said hopper in material-receiving position.
41. In a mining machine, a cutter, a hopper for receiving material severed by said cutter, guards carried by said cutter and arranged to overlap the sides of said hopper and to co-operate with said hopper to enclose the material severed by said cutter, and means for swinging said hopper upwardly between said guards for discharging said material.
42. In a mining machine, the combination with a supporting frame, of a supplemental frame pivotally connected to said supporting frame at the rear end of the latter, an arcuate sliding connection between said supplemental frame and the forward end of said supporting frame, core-cutting mechanism having an unobstructed core opening therethrough and mounted on the forward end of said supplemental frame for up and down movement on a horizontal axis, means for operating said core-cutting mechanism including feed thereof upwardly on such horizontal axis, and loading apparatus mounted on said supplemental frame in association with said core-cutting mechanism for taking the material cut by said core-cutting mechanism and moving such material automatically toward loading position rearwardly of said supporting frame, said loading apparatus comprising an endless conveyor extending longitudinally of said supplemental frame with its forward portion movable laterally with said core-cutting mechanism and with its rear end maintained in substantially the same position at all times during the operation of the machine to deliver the dislodged material to a mine car on a track back of the machine.
43. In a mining and loading machine, the combination with a supporting frame, of a supplemental frame pivotally connected to the rear end of said supporting frame and

slidably connected to the forward portion of said supporting frame, an endless conveyer mounted on said supplemental frame and extending longitudinally thereof for 5 operation from the forward portion of said supplemental frame toward the rear end thereof, core-cutting mechanism having an unobstructed core opening therethrough and mounted on the forward end of said supplemental frame for up and down movement on 10 a substantially horizontal axis, means for operating said core-cutting mechanism including upward feed thereof on such horizontal axis, and means co-acting with said 15 core-cutting mechanism to deliver dislodged material to said endless conveyer in the various positions of lateral adjustment of said supplemental frame relative to said supporting frame while the rear end of said conveyer remains in substantially the same position 20 for delivering dislodged material to a mine car on a track back of said supporting frame.

44. In a mining and loading machine, the 25 combination with a base frame, of a supplemental frame pivotally connected to said base frame and mounted thereon, an endless conveyer extending longitudinally of said supplemental frame and having a discharge 30 position near the pivotal connection between said supplemental frame and said base frame, a pivotal support between said supplemental frame and said base frame to enable said supplemental frame to be adjusted 35 to various angular positions relative to said base frame, core-cutting mechanism having an unobstructed core opening therethrough and mounted on the forward end of said supplemental frame for feeding movement 40 on a substantially horizontal axis, means for operating said core-cutting mechanism including upward feed thereof on such horizontal axis, and apparatus for gathering the dislodged material in advance of said 45 supplemental frame and delivering it to said conveyer for transfer toward loading position.

45. In a mining and loading machine, the 50 combination with a main frame, of a supplemental frame pivotally connected to said main frame and mounted on the latter for lateral movement relatively thereto, conveyer mechanism entirely mechanical for transporting dislodged material from the 55 front portion of said supplemental frame to a discharge position near its pivotal connection with said frame, core-cutting mechanism having an unobstructed core opening therethrough and mounted on the forward 60 end of said supplemental frame, apparatus also mounted on the forward end of said supplemental frame for gathering cut material and delivering it to the forward end of said transporting means, and means for 65 moving said supplemental frame laterally

about its pivotal connection on said main frame to adjust the position of said gathering apparatus in an arc relatively to said main frame.

46. In a mining and loading machine, the 70 combination with a supporting frame, of a supplemental frame pivotally connected to the rear portion of said supporting frame, a conveyer extending longitudinally of said supplemental frame and movable as to its 75 forward portion laterally with said supplemental frame along an arc with said pivotal connection as a center, core-cutting mechanism having an unobstructed core-opening 80 therethrough and mounted on the forward 85 portion of said supplemental frame, and means associated with said core-cutting mechanism for taking the dislodged material from its cut position and delivering it to said conveyer.

47. In a mining and loading machine, the combination with a main frame, of an elongated supplemental frame pivotally connected to said main frame, means for supporting the forward portion of said supplemental frame for adjustment in an arc on 90 said pivotal connection as a center, means for moving said supplemental frame laterally on said supporting means about said pivotal connection, core-cutting mechanism 95 having an unobstructed core opening therethrough and mounted on the forward portion of said supplemental frame, and loading apparatus for removing the dislodged material from the mine wall and delivering 100 it to a discharge position near said pivotal connection.

48. In a mining and loading machine, the combination with a main supporting frame, of a supplemental frame mounted thereon, a 105 pivotal connection between the rear portion of said supplemental frame and the rear portion of said main frame, a slide way on the forward portion of said main frame for supporting said supplemental frame for adjustment 110 in an arc about said pivotal connection as a center, rack and pinion mechanism for moving said supplemental frame on said slide way, a motor for operating said rack and pinion mechanism, core-cutting mechanism 115 having an unobstructed core opening therethrough and mounted on the forward end of said supplemental frame for feeding movement relatively thereto, and loading apparatus mounted on said supplemental 120 frame to move bodily in an arc therewith and comprising an endless traveling conveyer extending longitudinally of said supplemental frame to discharge position near said pivotal connection.

49. In a mining and loading machine, the combination with an elongated frame, of core-cutting mechanism having an unobstructed core opening therethrough and mounted on the forward end of said frame 130

- for feeding movement relatively thereto, a pivotal support near the other end of said frame, an endless traveling conveyer extending longitudinally of said frame and arranged to transfer material rearwardly along said frame, a slideway curved about said pivotal support as a center for supporting the end of said frame opposite said pivotal support, a motor and gearing for moving said frame on said slideway about said pivotal support to bring said core-cutting mechanism into various operating positions in a mine chamber, and means associated with said core-cutting mechanism for gathering the cut material and directing it onto said conveyer.
50. In a mining machine, an elongated frame, a pivotal support for one end of said frame, a conveyor extending longitudinally of said frame, a cutter carried by said frame at the end thereof opposite said pivotal support, a hopper movable independently of bodily movement of said cutter arranged to co-operate with said cutter and to raise the material severed thereby upwardly and discharge it rearwardly onto said conveyor, and a slideway for supporting the end of said frame carrying said cutter and arranged to permit lateral movement of said frame about said pivotal support to bring said cutter into different operating positions.
51. In a mining machine, the combination with a supporting frame, of means for transferring material from one location to another, said transferring means being mounted on a horizontal axis in fixed relation to said supporting frame, a chute pivotally connected to said supporting frame on a horizontal axis in fixed relation to said frame, said chute having a sliding engagement at the free end thereof with said transferring means, and means mounted on said supporting frame in fixed relation thereto for receiving material from said chute.
52. In a mining machine, the combination with a supporting frame, of means for lifting material to a predetermined position, said lifting means being pivoted to said supporting frame in fixed relation thereto, a device for scraping material from said lifting means when the latter reaches said predetermined position, said scraping device being pivoted to said supporting frame on an axis in fixed relation thereto, and a conveyer mounted on said frame in fixed relation thereto in position for receiving material from said scraping device and transferring such material to loading position.
53. In a mining machine, the combination with a supporting frame, of a scoop pivotally mounted thereon a substantially horizontal axis, a device pivotally mounted on said supporting frame on a substantially horizontal axis in fixed relation to said frame and in position for engaging a wall of said scoop to scrape material therefrom when said scoop reaches a predetermined position, and means for operating said scoop to gather material and deliver the same to said scraping device, said scraping device being then in position to direct material from said scoop toward loading position.
54. In a mining machine, the combination with a scoop having a curved portion near the axis of rotation and a wall extending outwardly therefrom, of a conveyor, and mechanism intermediate said conveyor and said scoop engaging the curved portion of said scoop until the latter reaches a predetermined position and then scrape the material from said wall of said scoop.
55. In a mining machine, the combination with a scoop somewhat S-shaped in cross section, of means for operating said scoop, and a device engaging an intermediate portion of said scoop to direct material therefrom when said scoop reaches unloading position.
56. In a mining machine, the combination with a supporting frame, of a hopper pivotally connected on a transverse axis for movement in advance of said frame, and an abutment pivotally connected to the lower forward end of said frame independently of said hopper by being disconnected therefrom but adapted to be moved into position for engaging the lower rear end of said hopper to hold the latter in predetermined position.
57. In a mining machine, the combination with supporting framework of a hopper having side walls, telescoping extensions for said side walls, means for moving said extensions relatively to said hopper to effect lengthening of the walls, and means for moving said hopper relatively to said extensions.
58. In a mining and loading machine, the combination with a supporting frame, of core-cutting mechanism having an unobstructed core opening therethrough mounted on said supporting frame for feeding movement relatively thereto on a substantially horizontal axis, a device connected to said frame in position to receive dislodged material from said core-cutting mechanism, and means for moving said receiving device to discharging position independently of movement of said core-cutting mechanism.
59. In a mining machine, the combination with a supporting frame, of a scoop pivotally mounted on the forward end of said frame, means for operating said scoop to gather material in advance of said frame and lift it for discharge rearwardly from said scoop, and a chute pivoted to said supporting frame and extending to a position for receiving the material from said scoop.
60. In a mining machine, the combination with a supporting frame, of a scoop pivoted thereto, means for operating said scoop to

- gather material and discharge the same rearwardly out of the rear end of said scoop, and a chute pivoted at its rear end to said frame on an axis having a fixed relation to 5 said frame and having a fixed relation to the pivotal axis of said scoop and being permanently in parallelism with the last-named axis, the forward free end of said chute being supported in position to receive material directly from said scoop as such material slides out of the rear end of such 10 scoop.
61. In a mining machine, the combination with a scoop, of a frame for carrying the same, guard mechanism extending vertically 15 to coat with said scoop to prevent material from falling laterally from the side of said scoop, means for adjusting the upright position of said guard mechanism relative to 20 said frame and relative to said scoop, and means for operating said scoop to gather material and discharge the same therefrom.
62. In a mining machine, the combination with a supporting frame, of a scoop pivoted 25 thereto, a guard plate extending upward from one side of said scoop directly above the latter, means for adjusting the upright position of said guard plate, and means for 30 operating said scoop to gather material and discharge the same therefrom.
63. In a mining machine, the combination with a supporting frame, of a scoop mounted thereon, upright guard mechanism extending upwardly above the side walls of 35 said scoop for preventing material from spilling from said scoop, means for adjustably holding said guard mechanism in fixed upright position relative to said frame, and means for operating said scoop.
- 40 64. In a mining machine, the combination with a supporting frame, of a scoop pivoted to the forward end thereof, spaced-apart guard plates closely associated with the sides of the scoop and extending upwardly from 45 the outer lateral surfaces of such scoop sides, means for moving the said guard plates upwardly beyond the initial position of said scoop and holding said guard plates stationary relatively to said frame, and means 50 for operating said scoop to gather a load in advance of said frame and move said load upwardly between said guard plates for discharge rearwardly between the upright planes of said guard plates onto said frame.
- 55 65. In a mining machine, the combination with a supporting frame, of conveyer mechanism mounted on said frame, core-cutting mechanism having an unobstructed core-opening therethrough and pivotally mounted 60 on said frame to swing on a substantially horizontal axis, and means also pivotally mounted on said frame in position to receive the severed material and raise it to a position above the said axis of said core-cutting mechanism and discharge said ma-
- terial from said receiving means onto said conveyer mechanism.
66. In a mining machine, the combination with a supporting frame, of a chute pivotally mounted on said frame on an axis 70 having a fixed relation to said frame, a scoop pivotally connected to said frame on an axis having a fixed relation to said frame and in parallelism with the axis of said chute and spaced from the chute axis, and means 75 for operating said scoop to gather material and discharge it rearwardly onto said chute.
67. In a mining machine, the combination with a supporting frame, of a chute mounted thereon for movement relatively thereto, a scoop mounted on said frame for pivotal movement relatively thereto on an axis having a fixed relation to said frame, and means for operating said scoop to gather material and discharge it out of the rear end 80 thereof by permitting such material to slide by gravity from said scoop onto said chute while said scoop lifts the forward end of said receiving chute but maintains delivery 85 relation with said chute.
68. In a mining machine, the combination with a supporting frame, of a scoop pivoted at the forward end of said frame, a chute mounted on said frame to have a sliding engagement at its forward free end with 90 the rear wall of said scoop, means for operating said scoop, to gather material in advance of said frame and discharge it rearwardly to said chute irrespective of the elevation of said scoop, and conveying mechanism mounted on said frame for receiving the material from said chute and transferring such material toward loading position.
69. In a mining machine, the combination with a supporting frame, of a scoop pivoted 105 at the forward end of said frame and having a curved extension near the pivotal axis of said scoop, a chute pivoted to said frame and having its forward free end in scraping relation to the curved extension of said 110 scoop, means for operating said scoop for gathering material in advance of said frame and delivering it to such chute out of the rear end of said scoop near such curved extension and while the forward free end 115 of said chute remains in scraping relation with said scoop extension, and a conveyer mounted on said frame in position for receiving the material from said chute and transferring such material toward loading 120 position at the rear end of said frame.
70. In a mining machine, the combination with a supporting frame, of a scoop pivoted at the forward end of said frame, a chute pivoted to said frame at its upper portion 125 and having a free forward end for engaging a wall of said scoop to scrape material therefrom when said scoop reaches a predetermined elevation, the forward end of said chute resting on the scoop by gravity, and 130

means for operating said scoop to gather material in advance of said frame and lift it to a position where said wall will be in substantial alinement with said chute for delivery of the material in said scoop to said chute.

71. In a mining and loading machine, the combination with a main frame having a rearwardly extending portion adapted to overhang a mine car on a track back of said frame, of a supplemental frame pivotally connected to the rear end of said main frame, apparatus for moving said supplemental frame laterally relatively to said main frame on the pivotal connection between said supplemental frame and the rear end of said main frame, two concentric drums each mounted between forwardly extending side plates of said supplemental frame for arcuate movement on a substantially horizontal axis, a gear fixed to one of said plates, a motor carried within the inner drum, loop-chain-core cutting mechanism having an unobstructed core-opening therethrough and connected to the inner drum to move in an arc therewith on the axis of rotation of said inner drum, power transmission mechanism connected to said motor for actuating said core-cutting mechanism, additional power transmission mechanism connected to said gear for effecting the feed of said core-cutting mechanism by moving such inner drum in an arc relatively to said spaced-apart plates, a hopper comprising spaced-apart side walls, a forward curved wall adapted to enter the kerf back of the core, a rear wall extending to the outer drum, an additional motor within said inner drum, power transmission mechanism between said additional motor and said outer drum for rotating said outer drum relatively to said inner drum to move said hopper from its lower receiving position at the floor of the mine chamber to its upper discharging position near the roof of the mine chamber, an endless conveyor extending longitudinally of said supplemental frame from a forward receiving position to an unloading position at the rear end of said supplemental frame, and a chute pivoted at its rear end to said supplemental frame near the forward portion of said conveyor and having its forward end movable freely up and down to correspond with the elevation of the outer drum and rear wall of said hopper to remain in scraping relation with the rear wall of the hopper when the material is discharged from said hopper through said core-cutting mechanism along said chute onto said conveyor for transfer to a mine car.

72. In a mining and loading machine, the combination with a main frame, of a supplemental frame mounted on said main frame for lateral movement of the forward por-

tion of said supplemental frame while the rear portion of said supplemental frame remains in substantially the same unloading position over a mine car, core-cutting mechanism mounted on the forward end of said supplemental frame for pivotal movement on a substantially horizontal axis and comprising a housing adjacent such axis, operating apparatus for said core-cutting mechanism, said operating apparatus being enclosed by said housing and comprising power transmission gearing for actuating and feeding said core-cutting mechanism relatively to said supplemental frame to cut an upright core of material in a mine wall in advance of said supplemental frame, a hopper journaled to said housing for arcuate movement relatively to said housing and relatively to said supplemental frame, means for operating said hopper to move the core of material upwardly and rearwardly, said last-named operating means comprising additional power transmission gearing enclosed by said housing, an endless conveyer extending longitudinally of said supplemental frame, and means for directing material from said hopper onto said conveyer when said hopper moves said core upwardly and rearwardly.

73. In a mining and loading machine, the combination with core-cutting mechanism, of a frame for supporting said core-cutting mechanism for feeding movement on a substantially horizontal axis, means for operating said core-cutting mechanism including feeding movement thereof on such axis, said operating means comprising mechanism for locking the core-cutting mechanism against bodily movement relatively to said frame when the operation of said operating means is discontinued, a core scoop pivotally mounted on said frame for movement on said axis independently of feeding movement of said core-cutting mechanism, an additional operating mechanism for moving said scoop upwardly while said core-cutting mechanism is locked against bodily movement, to remove the core from its native position through said core-cutting mechanism, and conveyor mechanism mounted longitudinally of said frame for receiving the material of the core and conveying the same to loading position.

74. In a mining machine, the combination with an elongated frame, of a sectional chute mounted thereon, the forward section being mounted for pivotal movement on a horizontal axis like the forward portion of said frame, a scoop mounted on a horizontal axis at the forward end of said frame, means for operating said scoop to gather material and discharge the same out of the rear end thereof onto the forward section of said chute, and an endless conveyor in the rear section of said chute for receiving

the material discharged by said scoop onto said forward section.

75. In a mining machine, the combination with an elongated supporting frame comprising a chute open at both ends and having a fixed relation to said frame, of conveyer mechanism extending longitudinally of said chute, a supplemental chute open at both ends and mounted in the forward end 10 of said first-named chute on a horizontal axis in fixed relation to said first-named chute, the scoop mounted on the forward end of said frame on a horizontal axis having a fixed relation to said frame and 15 spaced from said first-named chute in parallelism thereto, mechanism mounted on the forward end of said frame for dislodging material from an upright mine wall in advance of said frame, mechanism for operating 20 said dislodging mechanism, and means for operating said scoop to gather the dislodged material and discharge the same out of the rear end of said scoop onto the forward end of the said pivoted supplemental 25 chute for delivery to the conveyer mechanism on said first-named chute.

76. In a mining machine, the combination with an elongated frame having an open-ended chute, of a conveyer mounted longitudinally of said chute, a scoop mounted on the forward end of said frame for swinging movement on a horizontal axis in advance of said frame from a position below the forward end of said frame to a position 30 above, and a supplemental chute separate from said scoop but mounted at the forward end of said first-named chute and associated with said scoop to receive material from the latter and direct it onto said 35 conveyer.

77. In a mining and loading machine, the combination with supporting framework, of two concentric drums mounted on the forward end of said framework for arcuate movement on a substantially horizontal axis, a gear fixed to the said framework, a motor within the inner drum, loop chain core-cutting mechanism having an unobstructed core opening therethrough and connected to the inner drum to move arcuately therewith on the axis of rotation of said inner drum, power transmission mechanism connecting said motor to said core-cutting mechanism to drive the latter, additional 45 power transmission mechanism connected to said gear for effecting the feed of said core-cutting mechanism by moving such inner drum arcuately, means connected to the outer drum to move arcuately therewith in 50 position to engage the core, an additional motor within said inner drum, power transmission mechanism between said additional motor and said outer drum for rotating said outer drum relatively to said inner drum 55 to move said engaging means against the

cut core of material to transfer the latter away from the mine wall, and conveyer mechanism in position on said framework for receiving the core-material from said engaging means and transferring such 70 material toward loading position.

78. In a mining and loading machine, the combination with supporting framework, of core-cutting mechanism mounted on the forward end of framework for pivotal movement on a substantially horizontal axis and comprising a housing adjacent such axis, operating mechanism for said core-cutting mechanism, said operating mechanism being enclosed by said housing and 75 comprising power transmission gearing for actuating and feeding said core-cutting mechanism relatively to said framework to cut an upright core of material in a mine wall in advance of said framework, a core-moving device journaled to said housing for arcuate movement relatively to said framework, means for operating said core-moving device to move the core upwardly and rearwardly, said last-named operating 80 means comprising additional power transmission gearing enclosed by said housing, an endless conveyer mounted on said framework, and means for directing material from said core-moving device to said conveyer 85 when said device moves the core upwardly and rearwardly, said last-named operating 90 means comprising additional power transmission gearing enclosed by said housing, an endless conveyer mounted on said framework, and means for directing material from said core-moving device to said conveyer 95 when said device moves the core upwardly and rearwardly.

79. In a mining machine, the combination with supporting framework, of a hollow axle journaled in the forward end of said framework, a cutter carried by said axle, mechanism mounted within said axle for operating said cutter, a sleeve mounted on said axle, means carried by said sleeve in position for engaging the material severed 100 by said cutter, and mechanism located within said axle for rotating said sleeve relative to said axle to cause said moving means to transfer the cut material from the mine wall.

80. In a mining machine, the combination with supporting framework, of a hollow axle rotatably mounted in said framework, a U-shaped cutterbar carried by said axle, an endless cutter mounted on said cutterbar, a sleeve journaled on said axle, means carried by said sleeve in position to engage the material cut by said cutter, and means mounted within said axle for rotating said sleeve and said engaging means to cause 110 the latter to transfer material severed by said cutter to a position from which it may be transported.

81. In a mining machine, the combination with supporting framework, of a hollow axle journaled in said framework, a core-cutter carried by said axle, said core-cutter having an unobstructed core opening therethrough, mechanism mounted within said axle for rotating the latter and 115

130

said cutter to effect arcuate feed of the cutter, a motor for operating said rotating mechanism, said rotating mechanism including locking worm gear by which said 5 axle is held from rotation other than by said motor, means rotatable relatively to said axle in position for engaging the core and moving the same away from the mine wall, and mechanism mounted within said 10 axle for rotating said material-moving means relatively to said axle.

82. In a mining machine, the combination with supporting framework, of core-cutting mechanism having an unobstructed 15 core opening therethrough and mounted on the forward end of said framework for movement relatively thereto on a substantially horizontal transverse axis, core-moving mechanism mounted on said framework 20 in position to engage the lower end of the core, and yielding mechanism tending to rotate said engaging means with said core-cutting mechanism whereby said engaging means is held stationary in operative position 25 during the upward arcuate feeding movement of said core-cutting mechanism and ready to act to move the core from the mine wall when said core-cutting mechanism has completed the cutting of the core.

83. In a mining machine, the combination with supporting framework, of core-cutting mechanism mounted thereon and having an unobstructed core opening therethrough, means supported by said framework in position 30 for engaging the core, and yielding mechanism for holding said engaging means against the core until completely cut whereby said core will be moved from the mine wall by said engaging means immediately upon the core-cutting mechanism 35 completing the cutting of said core.

84. In a mining machine, the combination with supporting framework, of core-cutting mechanism pivotally mounted thereon and having an unobstructed core opening therethrough, means pivotally mounted 45 on said framework in position to engage said core, and means comprising a friction clutch for holding said engaging means 50 against said core yieldingly by reason of the slipping of said friction clutch during the operation of said core-cutting mechanism whereby said core will be moved by said engaging means from the mine wall immediately 55 upon the completion of the cutting of said core.

85. In a mining machine, the combination with supporting framework, of core-cutting mechanism pivotally mounted thereon and having an unobstructed core opening therethrough, means pivotally mounted 60 on said framework in position for engaging the core while being cut, mechanism operated upon feeding movement of said core cutting mechanism for yieldingly

holding said engaging means in operative position during such feeding movement of said core cutting mechanism, and means for positively holding the core-cutting mechanism from return movement during the operation of said engaging means after the core has been completely cut to move said core away from the mine wall. 70

86. In a mining machine, the combination with supporting framework, of core-cutting mechanism having an unobstructed core opening therethrough and pivotally mounted on said framework for arcuate feeding movement relatively thereto, means for operating said core-cutting mechanism comprising feeding mechanism embodying locking worm gearing to hold the core-cutting mechanism against arcuate movement after completing its stroke, means pivotally mounted on said framework in position to engage the core while being cut, and mechanism for yieldingly holding said engaging means against said core until the latter has been completely cut, and then moving said core from the mine wall while said locking worm gear holds said core-cutting mechanism against return movement. 85

87. In a mining machine, the combination with a supporting frame, of a supplemental frame pivotally connected to said supporting frame, core-cutting mechanism having an unobstructed core opening therethrough and mounted on said supplemental frame to rotate bodily therewith, means for operating said core-cutting mechanism comprising feed gearing between said main and supplemental frames and having therein a locking worm gear, a core-moving device rotatably mounted on said supplemental frame in position to engage the core but capable of occupying a stationary position back of the core during cutting of the latter, and means for rotating the core-moving device relatively to said supplemental frame while the latter is locked against rotary movement relative to said main frame, to effect movement of the core of material away from the mine wall after being completely cut. 95

88. In a mining machine, the combination with a supporting frame, of cutting mechanism mounted on said frame, means for operating said cutting mechanism including bodily upward movement thereof to sever a block of coal from a mine vein, and a device on said frame for positively supporting the block of coal in its original position in its native bed while it is being cut. 115

89. In a mining machine, the combination with a supporting frame, of cutting mechanism mounted thereon, means for operating said cutting mechanism including bodily movement thereof relative to said frame to sever a block of coal from a mine vein, and a device mounted on said frame in position to be moved relatively thereto under the 120

block of coal to support the same in its original position in the mine wall while it is being cut.

90. In a mining and loading machine, the combination with a supporting frame, of core-cutting mechanism having an unobstructed core-opening therethrough and mounted on said supporting frame for feeding movement relatively thereto on a horizontal axis, a device connected to said frame and adapted to occupy a stationary position during the operation of said core-cutting mechanism, to receive the dislodged material, and means for moving said receiving device upwardly to discharging position after the operation of said core-cutting mechanism.

91. In a mining machine, the combination of means for cutting a core of material from the material to be mined by cutting spaced-apart kerfs and a kerf at the back of the core, and a device for lifting the severed core of material from its native position to a position for transfer back from the mine wall in a general horizontal direction.

92. In a mining machine, the combination with core-cutting mechanism, of means for operating said core-cutting mechanism to cut an upright core in a mine wall, and mechanism for engaging the lower end of said core to move the core upwardly and rearwardly from the upright face of the mine wall for transportation rearwardly in a general horizontal direction.

93. In a mining and loading machine, the combination with core-cutting mechanism having an unobstructed core-opening therethrough, of conveying mechanism, and means for engaging the lower portion of said core to move the latter upwardly from the position originally occupied thereby in its native bed and discharging said core in large blocks onto said conveying mechanism.

94. In a mining machine, the combination with a supporting frame, of a hollow supplemental frame, a motor within said supplemental frame, actuating gearing within said supplemental frame and connected between said motor and said cutting mechanism, feeding gearing within said supplemental frame and connected between said motor and said supporting frame, and ejector mechanism journaled on said hollow frame for rotary movement relatively thereto.

95. In a mining machine, the combination with a supporting frame, of two relatively movable supplemental frames concentrically mounted on said supporting frame, severing mechanism carried by one of said supplemental frames, material-moving means carried by the other of said supplemental frames, means for driving the supplemental frame carrying the material-moving means from the other sup-

plemental frame, and means for holding the last-named supplemental frame from movement during the movement of said material-moving means.

96. In a mining machine, the combination with a supporting frame, of a gear fixed thereto, a supplemental hollow frame pivoted to said supporting frame for arcuate movement concentric with said gear, cutting mechanism carried by said supplemental frame, a pinion meshing with said gear and mounted within said frame for rotary movement on an axis parallel to the axis of said gear, means for transmitting power to said cutting mechanism, and a motor carried by said supplemental hollow frame connected to said pinion to drive the same to cause said supplemental hollow frame to move in an arc relatively to said supporting frame on the axis of said gear to effect feeding of said cutting mechanism.

97. In a mining machine, the combination with a main supporting frame, of a supplemental frame mounted on said supporting frame for movement relatively thereto, cutting mechanism mounted on said supplemental frame, means for operating said cutting mechanism including feeding means comprising locking worm gear to move said supplemental frame relatively to said main frame, material-moving means carried by said supplemental frame, and mechanism for operating said material-moving means including movement thereof relatively to said supplemental frame while the latter is held stationary relative to said main frame by said worm gear during the operation of said material-moving means.

98. In a mining machine, the combination with a main supporting frame, of a supplemental frame comprising a cutter head, of a loop chain core-cutter having an unobstructed core-opening therethrough and mounted on said cutter head for bodily movement therewith, means for operating said loop chain core-cutter including arcuate feed thereof by movement of said cutter head arcuately relatively to said main frame, a material-moving device mounted on said supplemental frame for arcuate movement relatively thereto, means for holding said cutter head stationary relatively to said main frame, and means for driving said material-moving device from said cutter head while the latter is held stationary against movement relatively to said main frame.

99. In a mining and loading machine, the combination with a main frame having spaced-apart side walls and a connecting bottom portion to form an open-ended chute, of an auxiliary frame mounted on said main frame and also provided with spaced-apart side walls and a connecting bottom portion to form an open-ended chute, core-cutting mechanism having an unobstructed core-

opening therethrough and mounted on the forward end of said auxiliary frame, and means for transferring dislodged material from the forward portion of said auxiliary frame along the bottom portions of both of said frames.

100. In a mining machine, the combination with a supporting frame, of two relatively movable supplemental frames concentrically mounted on said supporting frame, kerf-cutting mechanism carried by one of said supplemental frames, material-moving means carried by the other of said supplemental frames, means for operating said kerf-cutting mechanism including arcuate feed thereof relatively to said supporting frame, said operating means comprising locking worm gearing for the feed transmission, and means for driving the supplemental frame 20 carrying the material-moving means relatively to the other supplemental frame while the latter is held from movement relatively to said supporting frame by said worm gearing.
101. In a mining and loading machine, the combination with elongated supporting framework, of a laterally spreading platform connected to the forward end of said framework and adapted to occupy a position closely adjacent a mine wall, an endless

conveyer mounted on said elongated framework and having superposed portions traveling in opposite directions to and from a receiving position at the rear end of said platform, and self-acting power mechanism 35 mounted on said platform in position for dislodging material from the mine wall onto said platform and effecting the transfer of such dislodged material over said platform onto the receiving end of said conveyer at 40 the rear end of said platform.

102. In a mining machine, the combination with a supporting frame, of two relatively movable supplemental frames concentrically mounted on said supporting 45 frame, severing mechanism carried by one of said supplemental frames, material-moving means carried by the other of said supplemental frames, and means within the confine of said supplemental frames for 50 operating both the material-moving means and the severing mechanism.

In testimony whereof I have signed my name to this specification, in the presence of two subscribing witnesses, on this 12th day 55 of November, A. D. 1915.

EDMUND C. MORGAN.
